UNITED STATES PATENT OFFICE.

MILES B. DODGE, OF SAN FRANCISCO, CALIFORNIA, ASSIGNOR TO PARKE & LACY, OF SAME PLACE.

ORE-CONCENTRATOR.

SPECIFICATION forming part of Letters Patent No. 406,201, dated July 2, 1889.

Application filed July 6, 1888. Serial No. 279,208. (No model.)

To all whom it may concern:

Be it known that I, MILES B. DODGE, of the city and county of San Francisco, State of California, have invented an Improvement in 5 Concentrators; and I hereby declare the following to be a full, clear, and exact description of the same.

My invention relates to certain improvements in concentrators for valuable heavy 10 minerals or other substances.

It consists in certain details of construction, all of which will be more fully explained by reference to the accompanying drawings, in which—

15 Figure 1 is a perspective view of my apparatus. Fig. 2 is an enlarged perspective view of the upper part of the feed-hopper and the overflow-troughs. Fig. 3 is a longitudinal vertical section of the machine.

20 A is the inclined shaking-table, having the surface B covered with rubber, and upon this table the material is deposited by means of holes C in the box D, which extends transversely above the table, as shown. The material is delivered into the box D from the 25 segmental receiver E, being distributed by the rotary arms F, as shown.

20 G is a hopper, having a plug H, as shown, fitted into its lower end, with a small perforation of sufficient size to allow the thin pulp 30 to pass through as rapidly as may be desired, this pulp being discharged into the segmental receiver E. In order to separate the coarser material which would not pass through 35 the plug H, the spout I, which brings the material from the battery or other point of supply, discharges into the box J, having a screen bottom K, which permits only that portion which is sufficiently fine to pass through, the 40 other portion being removed or otherwise discharged from time to time.

The table A is caused to oscillate or vibrate endwise by means of a cam L and spring M, the cam forcing the table in the direction of 45 its length and toward the lowest point of its inclination with a gentle movement, while the spring M brings it back in the direction of its highest end with a sudden sharp motion, the movement being abruptly checked 50 by the upper end of the table striking against

the adjustable buffers N, this operation being similar to that shown in other machines of this class.

Water is supplied through holes in the pipe O, and, being discharged upon the upper end 55 of the table, flows downward, carrying the lighter material to the lower end of the table, while the heavy mineral is gradually brought toward the upper end by the constant jarring caused by the abrupt stoppage of the table, 60 as above described.

In feeding the pulp upon this class of tables considerable difficulty is encountered by reason of too great a supply of water with the pulp which is delivered upon the table, and 65 this seriously interferes with the proper action of the current discharged upon the upper end of the table from the pipe O.

In order to regulate the discharge of water and material upon the table, I have devised 70 the hopper G, above described, and the plug H at the lower end, having the small opening, enables me to provide a constant feed for the table, which is just sufficient, so that the current from the pipe O will do its work efficiently 75 in carrying off and discharging the gangue or lighter material, while the sulphurets and heavier material gradually move up the surface B. The trough D, extending across and near the surface of B, having the holes C 80 about an inch apart, will deliver the pulp upon the table properly distributed, and at the same time this arrangement of the holes leaves ample space between them for the flow of water and lighter material, which it is de- 85 sirable to have pass down the table.

In order to dispose of any surplus water and light material which is discharged into the hopper G, it is allowed to flow over the edges at P, Figs. 2 and 3, these edges being 90 somewhat lower than the top of the hopper, so as to allow the overflow to discharge into troughs Q upon each side of the hopper, and this discharge flows into the pipe R, by which it is led directly into the segmental receiver 95 S, which is constructed similarly to the one shown at E, this receiver having also the rotary arms or distributors T, similar to those at F. This lighter material is discharged over the bar U, which extends across the lower 100

edge of the receiver S, and the material thus discharged falls upon the lower portion V of the inclined table A. There is always a small portion of the heavier material which is pulverized so fine that it will not be carried upward against the moving current by the motions of the oscillating table, and this material will some of it pass downward through the pipe R and be received upon the table at 10 V, and some of it, passing from the table B over the transverse riffle W, will also fall upon the table V below the riffle, and the whole of it is stirred up and agitated by the pins X, which project downward from the bar U, so 15 as to dip into this material, the movements of the table causing these pins to act as stirrers in the same manner as if the pins themselves were movable. The heavy fine material which comes upon this table is thus 20 caused to settle to the bottom, while the lighter gangue flows off over the lower end, the riffles or steps Y arranged at this end preventing the more valuable portion from flowing off with it. This valuable material which 25 falls upon the table V is shoveled out from time to time and saved.

The upper end of the table B has a concave depression a, into which the sulphurets and other valuable heavy material are gradually 30 carried by the concussion of the table, and this mineral is discharged through the opening or passage b into a trough or receiver c. A considerable quantity of fine or floured mercury will always accompany the mineral, and if the discharge-opening b were level with 35 the surface of the table all this mercury would be carried out with the mineral. In order to separate it from this mineral and save it, an elevated portion d is formed in the concave 40 upper end a of the table. This elevation d has the opening b made through it. As the valuable heavy mineral accumulates so as to

be above the top of this elevation, it is manifest that it will discharge continuously from the opening b into the receiver c; but as the 45 mercury is considerably heavier than any other portion it will settle down into the depression or concavity a, and will not go off through the opening b.

Having thus described my invention, what I 50 claim as new, and desire to secure by Letters Patent, is—

1. The hopper G, provided with the box J, the screen K, and the troughs Q upon each side of the hopper, said troughs having the 55 overflow-edges P, in combination with the perforated plug H, for regulating the discharge from the hopper, substantially as herein described.

2. The hopper or receiver G, provided with 60 the screen K, the overflow-passages, and a regulating discharge-plug H, in combination with the segmental receiver E, the rotary distributing-arms F, and the box D, placed between the receiver E and the table B, and having 65 perforations C made through it, so as to leave space for the downward flow of material on the surface of the table B between the points where the pulp is supplied to the table, substantially as herein described.

3. The hopper G, provided with the screen K, the overflow pipes or passages, and the discharge-pipe R, in combination with the supplemental receiver S, distributor T, discharging 75 upon the surface V of the table below the riffle W, and the stirrers or agitators X, substantially as herein described.

In witness whereof I have hereunto set my hand.

MILES B. DODGE.
